US0D1075476S

(12) **United States Design Patent** (10) Patent No.: **US D1,075,476 S**
(45) Date of Patent: ** May 20, 2025

(54) **SMART LOCK**

(71) Applicant: **Guangzhou Lightsource Electronics Limited**, Guangzhou (CN)

(72) Inventors: **Qunzhi Huang**, Guangzhou (CN); **Yibiao Fang**, Guangzhou (CN)

(73) Assignee: **Guangzhou Lightsource Electronics Limited**, Guangzhou (CN)

(**) Term: **15 Years**

(21) Appl. No.: **29/862,815**

(22) Filed: **Dec. 13, 2022**

(51) LOC (15) Cl. **08-07**

(52) U.S. Cl.

USPC **D8/331**

(58) **Field of Classification Search**
